(57) CLAIM

The ornamental design for a golf glove caddy, as shown and described.

DESCRIPTION

FIG. 1 is a front perspective view of a golf glove caddy showing our new design;

FIG. 2 is a front perspective view on an enlarged scale thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of a modified form of a golf glove caddy showing our new design;

FIG. 10 is a front elevational view of FIG. 9;

FIG. 11 is a rear elevational view of FIG. 9;

FIG. 12 is a left side elevational view of FIG. 9;

FIG. 13 is a right side elevational view of FIG. 9;

FIG. 14 is a top plan view of FIG. 9;

FIG. 15 is a bottom plan view of FIG. 9;

FIG. 16 is a front perspective view of another modified form of a golf glove caddy showing our new design;

FIG. 17 is a front elevational view of FIG. 16;

FIG. 18 is a rear elevational view of FIG. 16;

FIG. 19 is a left side elevational view of FIG. 16;

FIG. 20 is a right side elevational view of FIG. 16;

FIG. 21 is a top plan view of FIG. 16; and,

FIG. 22 is a bottom plan view of FIG. 16.

The broken line showing of a belt and golf glove in FIG. 1, the showing of the word message as a location thereof in FIGS. 1, 2, 9 and 16 and the showing of particular spring clip in all the figures are for illustrative purposes and form no part of the claimed design.
